DESIGN FOR A LIQUID DISPENSER

Thomas L. Titus, Cheyenne, Wyo., assignor to The Wyatt Manufacturing Company, a corporation of Wyoming

Application March 24, 1941, Serial No. 99,817

Term of patent 14 years

To all whom it may concern:

Be it known that I, Thomas L. Titus, a citizen of the United States, residing at Cheyenne, in the county of Laramie, State of Wyoming, have invented a new, original, and ornamental Design for a Liquid Dispenser, of which the following is a specification, reference being had to the accompanying drawing, forming a part thereof.

Fig. 1 is a top plan view of a liquid dispenser,
showing my new design.

Fig. 2 is a side elevational view of the same.
Fig. 3 is a front elevational view of the same.
The dominant feature of the design resides in the portion shown in full lines.

I claim:

The ornamental design for a liquid dispenser,
as shown and described.

THOMAS L. TITUS.
